JOHN T. S. BROWN, JR., OF PROSPECT, KENTUCKY.

PUMP.

1,156,052.

Specification of Letters Patent. Patented Oct. 12, 1915.

Application filed February 1, 1915. Serial No. 5,462.

To all whom it may concern:

Be it known that I, JOHN THOMPSON STREET BROWN, Jr., a citizen of the United States, residing in Prospect, county of Jefferson, and State of Kentucky, have invented a certain new and useful Improvement in Pumps, of which the following is a specification.

An object is to produce a double acting pump of the class described. Double acting pumps of this character have been produced before, but the structural arrangements have been such that the effective area was reduced so that the output was increased but little over that of a single acting pump having a working chamber of the same diameter, consequently these pumps have not come into general use.

Another object of this invention is to provide a pump of the class described, having a "straight line" working chamber, the effective area of which is not reduced by the structural arrangement and which will consequently have an output of substantially double the quantity of a single acting pump of the same diameter and stroke.

A further object is the provision of a pump of the class described which will be economical in construction, efficient and durable in service.

With the foregoing and other objects in view, the invention has particular relation to certain new and novel features of construction illustrated in the accompanying drawing which forms a part of this specification wherein is set forth an embodiment of the invention, but it is to be understood that such changes and modifications may be resorted to as come within the scope of the appended claims.

Referring to the drawing wherein similar reference characters designate like parts in the several views; Figure 1, is a central vertical section, with portions broken away and parts in elevation, showing the plunger at the commencement of its upward stroke; Fig. 2, a perspective, of the upper valve case Fig. 3, an elevation of a modification of the upper valve cage showing one depending valve in position thereon; Fig. 4, a perspective of the annular valve; Fig. 5, a section on line X—X, and Fig. 6, a section on line Y—Y of Fig. 1. Fig. 7, a bottom plan of the valve illustrated in Fig. 3.

Referring now more particularly to the drawing, the numeral —1— designates a

section of tubing, comprising the working chamber of the pump, having a lining —2—, of noncorrosive material, which extends from the lower end, to within a spaced distance of the upper end thereof.

A suitable inlet valve —3—, is removably secured in the lower end of the working chamber by suitable means, that illustrated herewith is of the type well known in the art as a ball valve, and comprises a cage —4— and a ball —5— adapted to close on an inlet —6—. Within the working barrel is a piston, or plunger —7—, having a central passage —8—. The plunger is provided with a plurality of piston rings —9— and is surmounted by a domed cover, or cage —10— within which is a ball valve —11—, which controls the flow of fluid through the passage 8. Ribs —12—, which extend from the inner surface of the cage 10 serve to center the ball valve 11 and to limit its travel. Connected to the upper end of the cage 10, and in communication with the interior thereof, is a hollow piston rod —13— provided on its upper end with suitable means for the attachment thereto of a pump rod which may be extended upward to a point of connection with a suitable actuating force. The piston rod is provided, near its upper end, with a plurality of openings, or outlets, —15— the total area of which is equal to, or greater than that of the passage through the piston rod. A valve cage —16— is positioned near the upper end of the working chamber. This valve cage composes an annular ring —17— disposed about the piston rod, and spaced from the sides of the tube 11 by lateral arms, or lugs, —18—. Legs —19— depend from oppositely disposed lugs 18 and are connected with an annular valve seat —20— which fits snugly within the tube 1 and is spaced from the piston rod leaving a passage —27— therebetween. The valve seat 20 has a beveled seat —21— on its outer lower edge which contacts closely with an oppositely disposed bevel face —22— on the upper end of the lining 2, forming a water tight connection therewith. The valve cage is secured in position by suitable means, such as screws —23, 24—, which extend through the tube and engage respectively in the lugs 18 and the valve seat 20. A sleeve —25— adapted to fit on the piston rod, has an annular enlargement —26— which seats on the valve seat 20 and forms a cut off valve which closes the pas-

100

sage 27. An annular flange —28— depends from the valve seat 20. A plurality of inlet openings, or ports —30— are disposed about the walls of the working chamber, opening 5 into that portion which is above the plunger when it is at the upper end of its stroke, the flow of fluid therethrough being controlled by valves —31— each of which comprises a body portion —32— the face of which is 10 contoured to form to the curvature of the walls of the chamber, and faced with a layer of suitable packing material —33—, secured thereon by suitable means such as metallic plates —34—. The valves 31 are carried on 15 the end of flexible members —35— which are secured by suitable means to the flange 28 on the inner surface thereof. In Figs. 3 and 7 I illustrate a modification of the upper valve cage 16, in which a plurality of legs 20 —48— are employed, instead of the annular flange 28; the inner face of the legs 48 are curved transversely. The springs 35 are secured on the legs by means of bolts —50 and 51— positioned respectively on each side 25 of the apex of said curved face. This construction affords means of adjusting the tension of the members 35. A delivery tube —40— is connected to the tube 1 by means of a reducing ring —41—. It is to be ob- 30 served that the passage through the plunger, the hollow plunger rod, the outlet therefrom, and between the piston rod and the sides of the tubes are of substantially the same area as those through the foot valve and the side 35 inlet valves, consequently as the space above and below the plunger is of equal capacity there will be delivered on each stroke, up and down, of the plunger, an equal quantity of water, and, that this would be double the 40 quantity that would be delivered by a single acting pump having a working chamber of the same diameter.

The operation of my improved pump is as follows: When the piston is on the up 45 stroke as illustrated in Fig. 1, water is drawn in through the foot valve 3 filling the lower portion of the working chamber, and water which is held in the portion of the chamber above the piston is forced upward, 50 the pressure serving to close the side inlet valves 31 and to raise the valve 26 on the piston rod, as shown this opens up a free communication between the working chamber and the discharge tube through the pas- 55 sage 27. It is obvious that during this operation the ball valve 11 is forced down by the pressure of the water and closes the passage 8 through the plunger 7. When the piston is forced downward the pressure will 60 close the foot valve 5 and the water beneath will be forced up through the passage 8, lifting the ball valve 11 and passing through the piston rod enter the discharge tube 40 through the opening 15.

65 It will be observed that during the down-

ward travel of the plunger the water in the discharge tube 40 is prevented from entering the upper portion of the working chamber by the closing of the check valve 26, which is held closed by the weight of water pressing down thereon. At the same time the upper part of the chamber is refilled through the side ports 30. It will be seen that a continuous flow of water is maintained through the discharge tube during 75 the operation of the pump. It will be observed that the arrangement illustrated permits of a ready removal of parts for repairs and adjustments.

Having thus described my invention so 80 that anyone skilled in the art pertaining thereto may make and use the same, I claim:

1. A pump comprising a working barrel, a reciprocable plunger therein having a vertical passage, an inlet valve in the lower end of said barrel adapted to admit water below said plunger, ports in the side of said barrel adapted to admit water above said plunger, a domed cover on said plunger, a valve adapted to close said passage, a hollow piston rod extended upward from said cover and having a plurality of lateral openings near the upper end thereof, a guide ring disposed about said piston rod, lugs 90 extended from said ring and secured to said barrel, an annular valve seat positioned below said ring and connected therewith, an annular valve disposed about said piston rod and adapted to close on said seat, valves depending from said valve seat and adapted to close said ports.

2. In combination, a working barrel connected with the lower end of a discharge tube, a reciprocable hollow piston in said barrel, a hollow piston rod extended from said piston upward into said discharge tube, said rod having lateral outlets into said tube, a valve in the lower end of said barrel, ports in the side of said barrel above said piston, a valve in said piston, a valve cage in the upper end of said barrel, said cage comprising a guide ring for said piston rod and an annular seat, an annular valve disposed about said rod within said cage and 115 adapted to close on said seat, valves depending from said cage adapted to close said ports.

3. In a pump, a valve cage comprising a guide ring, lugs extended radially therefrom, legs depending from said lugs, an annular valve seat carried by said lugs, an annular flange depending from said seat resilient members secured to and depending from said flange and valves attached to the 125 lower ends of said members.

4. In a pump, a valve cage comprising a guide ring, an annular valve seat connected therewith but spaced below, an annular valve adapted to close on said seat, and lat- 130

erally operable valves suspended from said cage.

5. In a pump, a barrel, a piston reciprocably positioned therein, a rod extended upward from said piston, said barrel having inlet ports in the side thereof above said piston, a valve cage through which said rod passes, said cage comprising a guide ring, an annular valve seat spaced below, an annular valve adapted to close on said seat, laterally operable valves adapted to close said ports, resilient arms depending from said cage to the lower ends of which said valves are secured.
15. 6. In a pump, the combination of a working chamber having a port, a piston working in said chamber below the port, an annular seat secured within the working chamber

ber above the port, a valve for said seat, a flexible member carried by and depending 20 from said annular seat and a valve for closing the port carried by said flexible member.

7. In a pump the combination of a working chamber, a lining for said chamber, the said lining terminating below the top of 25 said chamber, a port through said chamber and its lining, an annular seat for a valve secured within the chamber and resting on the upper end of the lining, a valve adapted to rest on said seat, a flexible member depending from the seat and a valve secured to said member for closing the port.
